UNITED STATES PATENT OFFICE.

CHARLES PEASE, OF LYNN, MASSACHUSETTS, ASSIGNOR TO XPEDITE MACHINE COMPANY, OF BERWICK, MAINE.

MACHINE FOR FINISHING HEELS OR OTHER PARTS OF BOOTS OR SHOES.

SPECIFICATION forming part of Letters Patent No. 743,988, dated November 10, 1903.

Application filed February 12, 1901. Serial No. 46,995. (No model.)

To all whom it may concern:

Be it known that I, CHARLES PEASE, a citizen of the United States of America, and a resident of Lynn, county of Essex, Commonwealth of Massachusetts, have invented certain Improvements in Machines for Finishing Heels or other Parts of Boots or Shoes, of which the following description, read in connection with the accompanying drawings, is a specification.

The invention relates particularly to machines for applying wax to the edges of heels of boots and shoes and rubbing the waxed heel to produce a finished surface thereon.

The present invention is especially useful when applied to machines in the use of which carnauba-wax is employed in finishing the heel. This wax, either pure or in preparations containing it in a large proportion, is preferable for use in finishing leather surfaces, because it gives a permanent bright polish and does not mold. Surfaces which are finished by the use of compounds of other waxes are likely to "mold"—that is, they are likely to turn a grayish color—and as leather surfaces finished with carnauba-wax retain their bright polish and do not mold this wax is generally preferred for such work. It has been found preferable to melt carnauba-wax before using it and to apply it in liquid form to the work member of the machine. It is characteristic of carnauba-wax, however, that it solidifies very quickly, becoming lumpy and unfit for use in finishing a leather surface, and in using it difficulty has been experienced in delivering it to the work member in proper condition for application to the work. To overcome this difficulty, I have devised mechanism for insuring the delivery of the wax to the work member in melted condition. To this end I have employed, in combination with the work member and with wax-supplying means, a conveyer for transferring the wax to the work member and means for heating the conveyer, whereby the melted and hot wax is delivered directly to the part which is in engagement with the work. It will, however, be understood that while the present invention is especially useful in its application to machines in the use of which carnauba-wax is employed the in-

vention is of course not limited to such use, and many of its features may be employed to advantage on machines in the use of which other kinds of wax are employed.

Of the drawings, Figure 1 is a perspective view of the machine looked at from an elevation back of the machine. Fig. 2 is a plan view of the machine. Fig. 3 is a vertical section through the machine-column. Fig. 4 is a detail on the vertical section-line 4-4, Fig. 2. Fig. 5 is a plan view showing the wax-holder and wax-conveyer and connections. Fig. 6 is a plan of parts shown in Fig. 5 with a plurality of wax-conveyers. Fig. 7 is a detail showing the spring for holding the wax-holder in elevated position. Fig. 8 is an elevation, on an enlarged scale, showing the wax-spreader and connections. Fig. 9 is a section on line 9 of Fig. 8.

On the shaft 2 is a loose pulley 4, to which the driving power is applied by belt from any suitable source. Said pulley has a friction-faced part 6 for engaging a similar part 10 on pulley 22, and connected therewith is a shipper device with handle 8, whereby in order to start or stop the machine said pulley 4 is moved endwise on shaft 2, it being thus engaged with or released from pulley 22. A belt 20, passing round the pulley 22, idlers 24 26, and pulley 28, operates for rotating the shaft 30. On the top end of shaft 30 is a spiral gear 32 in mesh with a similar gear 34 on the horizontal shaft 36, which shaft 36 is journaled for movement rotatively in the part a 85 of the head 38, and it carries the work member 40. A second shaft 42 has support for movement rotatively in the arm 44, which arm in turn is supported on the head 38. The shaft 42 carries on its outer end a tool 46, 90 such as is commonly in use for beading the boot or shoe heel seat, and in close proximity on said shaft are the cloth-covered polishing-tool 48 and the brush 50. Pivotaly connected with the machine-head are hoods 52 54, located above the members 48 50, respectively. Said shaft 42 also carries a pulley 56, which is connected by a belt 58 with pulley 60 on shaft 36, whereby motion is imparted from shaft 36 to revolve shaft 42. The head 38 is formed to enter the machine-column, its bottom end being supported on the screw 62,

which screw has threaded engagement with the machine-column and may be actuated for lifting and lowering the machine-head to different altitudes. The shaft 30 has spline-and-key engagement with pulley 28 in order that the shaft-actuating mechanism shall automatically adjust itself to any change in the altitude of the head. The head 38 also is permitted rotative movement in the machine-column, whereby to shift the positions in a horizontal plane of the mechanisms supported thereon, and when suitably stationed the head may be securely clamped in the machine-column by operating the screws 66 68, to which end the column is cut longitudinally on line 70.

The work member 40 may be of any suitable construction, but preferably is of the type shown and described in detail in United States Letters Patent to Baudry, No. 616,432, dated December 20, 1898. The work member as shown herein is heated by gas conducted from a suitable supply through the pipe 74, and the plate 76 is set in position for resting the tread-surface of a boot or shoe heel while it is being treated by the work member.

In a bracket 80 on the machine-head 38 is the shaft 82. On said shaft is a worm-gear 84 in mesh with a worm 86 on the shaft 36. Said shaft 82 carries in the top end the eccentric-pin 88, which enters the groove 90 in a plate 92 on a shaft 94, and this combination reciprocates the shaft 94 endwise. The shaft 94 carries a part 98, which is loose thereon and embraces by a strap 99 a nut 100, which nut has screw-threaded engagement with shaft 94 and may be turned for shifting the position of part 98 on shaft 94 longitudinally. A carrier 102 is connected pivotally with part 98 by means of the pin 104, on which the carrier has a free rocking movement. Said movement is limited by the walls 106 108 on said carrier bringing up against the part 98. (See Fig. 9.) On the outer free end of carrier 102 is a brush 110, which is detachably connected with the carrier by a screw 112. Said brush rests upon the face of the work member 40, being depressed theretoward by the weight of carrier 102, and obviously it is moved across said face by the endwise movement of shaft 94. The carrier 102 is mounted to turn on pivot 104, and the convexed surface of the member 40 acts as a fulcrum beneath the brush 110, so that when the brush is moved across said face the line of weight or pressure of the carrier 104 on said brush passing from one side to the other side of the highest part of said face will cause the brush to rock over the said highest part of said face and contact with the part or section of the face of the work member which is disposed on the side toward which the brush is rocked. This combination operates for distributing and spreading wax on the face of the work member and will automatically adapt itself to the various shapes and sizes of different work members.

Supported to turn on the bracket 80 is a handled part 120, which carries a rod 122 in

position to limit the movement of the part 98, (see Fig. 8,) and by suitably turning the part 120 about the axis of shaft 94 to shift 70 the rod 122 the carrier 102 may be lifted for removing brush 110 from the face of the work member 40.

The wax is supplied from a wax-holder 130, which comprises an inclined hopper or guideway 131 for holding unmelted wax, and extending across the lower end of the guideway 131 is a narrow trough-like compartment 133. The narrow trough-like compartment 133 receives the lower portion of a conveyer 132, which consists of a metallic wheel fast to a shaft having a rigid portion 135 and a flexible portion 136. The rigid portion 135 of the shaft is mounted in a bearing 137 in a casting 150, (see Fig. 5,) and the flexible part is 75 connected to the lower end of the positively-driven shaft 82, above described. Said connection is made by a sleeve 140, which carries a spring-actuated plunger 142 in position to enter a socket 144 in said shaft, whereby 80 is secured a grip sufficient to turn the conveyer under normal conditions, but adapted to slip in case movement of the conveyer is resisted abnormally—for example, by the unmelted wax in said holder. To prevent the 85 sleeve 140 from becoming detached from the shaft 82, a groove is cut in shaft 82, which terminates in the socket 144, so that the plunger 142 when it is lifted from the socket 144 will travel in said groove. The conveyer 100 is preferably heated, and a gas-pipe 134 is shown for this purpose. The wax-holding guideway is so located with relation to the trough-like compartment in which the conveyer rotates that the wax slides by gravity 105 down the guideway against the side of the conveyer-wheel 132. The heat for the conveyer may be so regulated that the wax is melted as fast as it is needed, and the melted wax flows down into the trough 133, which is 110 so narrow that it is nearly filled by the conveyer-wheel. The wheel keeps the liquid wax in the trough hot and as it rotates in the direction of the arrow thereon delivers the hot wax to the work member 40. As 115 shown in the drawings, the conveyer is so located with relation to the work member that the wax is delivered to the work member from the portion of the conveyer-wheel which is just above the top of the trough 133. 120 The arrangement of the parts is such that only a small quantity of wax is kept melted, and the narrow trough which holds the liquid wax and the conveyer are so located with relation to the work member that the melted 125 wax is kept hot and is but little exposed to the air in being delivered to the work member.

The casting 150, in which the shaft 135 of the conveyer is journaled, is an arm pivotally mounted on a sleeve 153 of a collar 154, fastened on a rod 152, which is projected from the frame of the machine, (see Figs. 5 and 7,) and the collar 154 has an arm or projection in which is mounted an adjusting-screw 156.

The screw 156 engages the lower side of the arm or casting 150 and adjustably supports the outer end of said arm and the conveyer 132, carried thereby. By operating the adjusting-screw the conveyer may be positioned nearer to or farther from the work member 40 for the purpose of causing the conveyer to deliver more or less wax to the said member. It is also obvious that the screw 156 may be employed to move the conveyer into and out of operative position. When in its operative position, the conveyer 132 is not required to be in touch with the face of the work member; but when it is approximately close to said face the wax is taken from said conveyer, it being seemingly sucked off by the heated rapidly-moving work member, and thereafter the wax is spread over said face by the brush 110. The amount of wax taken may be regulated by the distance between the conveyer and the face of the work member, as above stated. Another way of regulating the quantity of wax taken is by varying the temperature of the conveyer, as when very hot it will carry a thinner film of wax, and consequently deliver less to the work member than when it is less heated, and still another way is to vary the speed of its movement. In Fig. 6 two conveyers are represented, which may be employed whenever it is desirable to deposit the wax on different circumferential surface lines of the face of the work member, and obviously a greater number of conveyers could be used if it should become desirable for any reason to do this. The sleeve 153 also pivotally supports an arm 200, which carries the wax-holder 130. The hub 201 of the arm 200 is chambered out to cover a spring 202, which surrounds the sleeve 153 and has one end secured to the sleeve. The other end of the spring is turned outwardly and provided with a handle 204, which is adapted to engage in a notch 208, extending obliquely into the hub 201. The spring 202 therefore serves to detachably secure the hub 201 of the arm 200 on the sleeve 153 and also acts on the arm 200 to tend to raise the end thereof which carries the wax-holder 130. The arm 200 is stopped in its uppermost position by contact with the bearing of shaft 135. The spring 202 thus constitutes yielding means for sustaining the wax-holder in operative relation to the conveyer. The arm 200 and the wax-holder may be removed in order to substitute another holder containing a different kind or quality of wax. When a wax-holder which has before been used and in which the trough 133 normally occupied by the conveyer is filled with unmelted wax is put in place, the unmelted wax in the trough is pressed against the conveyer by the spring 202. The spring supports the wax-holder, with the unmelted wax pressed against the conveyer, until during the operation of the machine the heated conveyer melts the wax in the trough. When the wax becomes melted, the spring forces the

holder up into its normal position, where it is stopped by contact with the bearing of the conveyer-shaft. 70

In use the work member 40 is preferably heated to a higher temperature than the wax-conveyer 132. This renders the semiviscous wax on the conveyer 132 susceptible to the drawing influence of the rapidly-moving member 40, and it also causes the wax to become heated to a very high degree on the face of the member 40 preparatory to deposit on the surface of the work. The wax-treated surface as it comes from member 40 is somewhat rough, and it is next applied to the cloth-covered tool 48, which smooths over the outer face of the wax film. The heel is next applied to the beading-tool and finally to the polishing-brush 50. It is found desirable for 80 the workmen, having once taken the boot or shoe in hand, to apply it to all of these tools before putting it down. This makes it important to assemble all said work members or tools in such positions that they will be 90 accessible to the workmen without traveling. The shafts 36 and 42 therefore are terminated at unequal distances from the axis of the machine-head, and the work member 40 is stationed on the end of shaft 36. This allows 95 the shafts to be set close together, so that a workman standing in position of work relation to shaft 42 may without walking reach forwardly to the work member 40.

The work member 40, it will be understood, 100 is designed for finishing the surfaces of boot and shoe heels and has its working face convexed cross-sectionally in substantial counterpart of the concave cross-sectional line of the heel to be finished. It is of course obvious 105 that a work member shaped for treating other surfaces than boot and shoe heels could be substituted for the work member 40.

Having fully described the nature of my invention and the best form of it now known to 110 me, what I desire to claim, and secure by Letters Patent of the United States, is—

1. A machine of the class described, comprising a work member for engaging and imparting a finish to the surface of the work, 115 means for supplying wax, a conveyer for transferring wax from said supplying means to said work member; said conveyer being out of contact with the work, and means to heat the wax while it is on the conveyer whereby 120 the wax is delivered in liquid form to the work member.

2. A machine of the class described, comprising a work member for engaging and imparting a finish to the surface of the work, 125 means for supplying wax, means for transferring wax from said supplying means to said work member and for distributing the wax over the working face of said work member, said transferring means being out of contact with the work, and means for heating the wax while it is on said transferring means. 130

3. A machine for the purpose stated, comprising a work member, a medium bearing on

the face of said member, and means for causing the medium to rock on said face for spreading wax thereover.

4. A machine for the purposes stated, comprising a work member with a working face of convexed cross-sectional contour, means to rotate the member, a medium extending transversely of the said working face, and means for causing the medium to rock on said face for spreading wax thereover.

5. A machine for the purpose stated, comprising a work member, provided with a working face of convex, cross-sectional contour, means for moving the member to do its work, a medium in juxtaposition with said working face and supported for rocking movement, and means to move it in a line transversely of said working face for spreading wax thereover.

10 6. A machine for the purpose stated, comprising a work member, a movable part, a carrier connected pivotally with said part and having on its free end a medium bearing upon said work member, and means for moving said part in a line transversely of said work member for spreading wax thereover.

7. A machine of the class described, comprising a work member for acting on the surface of the work, means for supplying wax to said work member and means for distributing the wax over the working face of the work member, said supplying means being out of contact with the work, and means for heating said supplying means whereby the wax is delivered in liquid form to the work member.

8. In a machine of the class described, a work member, a wax-holder, a conveyer for the wax supported independently of the wax-holder and out of contact with the work, and being arranged to deliver wax directly to the work member, and means to heat the wax while on said conveyer.

9. In a machine of the class described a wax-supplying mechanism, comprising a wax-holder, a wax-conveyer, and means for heating the conveyer, the wax-holder having provision for holding unmelted wax adjacent to the heated conveyer and having a compartment for receiving the melted wax and from which the wax is taken by the conveyer.

10. A machine for the purpose indicated, comprising a work member and a rotatable conveyer for transferring wax to said member, said conveyer and said work member being supported out of contact but in close relation.

11. In a machine of the class described a work member, a conveyer, out of contact with the work, for delivering melted wax at a point adjacent to the work member, means for heating the work member and means for rotating said member rapidly whereby the melted wax is drawn off the conveyer onto the work member.

12. In a machine of the class described a work member, a conveyer for delivering

melted wax at a point adjacent to the work member, means for adjusting the relation of the conveyer to the work member, means for heating the work member, and means for rotating said member rapidly whereby the melted wax is drawn off the conveyer onto the work member.

13. In a machine of the class described a work member for acting on the surface of the work, actuating mechanism therefor, and a wax-supplying mechanism comprising a conveyer for delivering wax to the work member, means for actuating the conveyer, a holder adapted to contain unmelted wax, and yielding means for supporting the holder with the wax pressed against the conveyer.

14. In a machine of the class described a work member for acting on the surface of the work, actuating mechanism therefor, and a wax-supplying mechanism comprising a conveyer for delivering wax to the work member, means for actuating the conveyer, a holder adapted to contain unmelted wax, yielding means for supporting the holder with the wax pressed against the conveyer, and means for heating the conveyer to melt the wax whereby the wax is delivered in liquid form to the work member.

15. A machine for the purpose stated, comprising a work member, a medium for holding meltable wax, a rotatable conveyer for transferring the wax to said work member, means for heating the conveyer whereby the wax is melted, means for holding the conveyer and wax-holding medium in positions relatively to each other before the wax is melted, and for holding the conveyer and wax-holding medium in different positions relatively to each other after the wax is melted.

16. A machine for the purpose stated, comprising a work member, a wax-holder, a conveyer to transfer the wax from said holder to the work member, means for heating the conveyer whereby the wax in the holder is melted, means for holding the said holder and said conveyer in one position relatively before the wax is melted, said means being set in operation by melting of the wax for automatically shifting the holder and conveyer relatively.

17. A machine for the purpose stated, comprising a work member, a conveyer and means to move it for transferring wax to said member, said means being rendered inoperative by abnormal resistance of the conveyer.

18. A machine for the purpose stated comprising a work member, a holder for wax, a conveyer operating in said holder for transferring said wax to said member, said holder being supported for removal independently of the conveyer.

19. A machine of the character indicated, comprising a work member, a wax-holder, means for heating the wax in said holder, a conveyer out of contact with the work for transferring the wax to said member, means

for heating the wax while it is on the conveyer, and means for further heating the wax while it is on the work member.

20. In a heel-finishing machine, a rotary work member, a rotary device arranged out of contact with the work for delivering wax to the work member, and means for heating said rotary device.

21. In a machine of the class described, a work-rubbing member, a wax-supplying means, a conveyer for delivering wax from the wax-supplying means to the work-rubbing member, means for heating the wax while it is on the conveyer, and means whereby the workman may render the conveyer operative or inoperative for delivering wax.

22. A machine for finishing heels comprising a work-rubbing wheel, a roll out of contact with the work, and means for heating the roll, said roll being adapted to occupy an operative position adjacent to the work-rubbing wheel, in combination with means under the control of the workman for moving said roll toward and from operative position.

23. In a machine of the class described, a work member for applying wax to the surface of the work, a wax-holder, a conveyer for transferring wax from the wax-holder to the work member, means for directly heating the conveyer whereby the wax is delivered hot to the work member, and means under the control of the workman for moving the wax-holder and the conveyer toward and from the work member.

24. In a machine of the class described, a work member for applying wax to the surface of the work, in combination with a movably-supported wax-holder, a movably-supported wax-conveyer, yielding means for sustaining the wax-holder and conveyer in operative relation to one another, and means for adjusting the position of the wax-holder and conveyer with relation to the work member.

25. In a machine of the class described, the combination with a work member for applying wax to the surface of the work, of a wax-holder and a wax-delivering device arranged out of contact with the work, together with means under the control of the workman for moving said holder and delivering device into and out of operative relation to the work member, said means having provision for supporting said holder and delivering device away from the work member.

26. In a machine of the class described, a work member for applying wax to the surface of the work, in combination with a wax-holder and a wax-delivering device mounted to rotate in the wax-holder, said delivering device being arranged out of contact with the work, and means under the control of the workman whereby said wax-holder and wax-delivering device may be moved toward and from operative position and supported away from the work member when not in operative position.

27. In a machine of the class described, a work member for applying wax to the surface of the work, in combination with movable supporting means, a wax-holder carried thereby, and a wax-delivering device also carried by said supporting means and mounted to rotate in the wax-holder, and means under the control of the workman whereby said supporting means may be actuated to move the wax-holder and the delivering device into and out of operative relation to the work member, said actuating means having provision for sustaining the holder and delivering device in inoperative position.

Signed by me at Lynn, Massachusetts, this 9th day of February, 1901.

CHARLES PEASE.
